UNITED STATES PATENT OFFICE.

HENRY C. TABRETT AND WALTER LEWIN, OF SAN FRANCISCO,
CALIFORNIA.

EVAPORATOR.

No. 801,346.

Specification of Letters Patent.

Patented Oct. 10, 1905.

Application filed February 26, 1904. Serial No. 196,471.

To all whom it may concern:

Be it known that we, HENRY C. TABRETT, residing at 3847 Twenty-first street, and WALTER LEWIN, residing at 1227 Page street, in the 5 city of San Francisco, county of San Francisco, State of California, citizens of the United States, have invented certain new and useful Improvements in Evaporators; and we do hereby declare the following to be a full, clear, and 10 exact description of said invention, such as will enable others skilled in the art to which it most nearly appertains to make, use, and practice the same.

This invention relates to evaporation, and 15 particularly to machines for the derivation of fresh or pure water from sea or foul water.

The invention consists, primarily, in dividing the apparatus into units of novel construction and arrangement and operating them in 20 batteries.

Heretofore apparatus of this class have been built in single units of the desired capacity, which have proven cumbersome and difficult to repair, this latter necessitating the shutting 25 down of the whole apparatus. This class of mechanism has its widest use on shipboard where available space is limited or irregular in shape, the installation being often accomplished with difficulty and resulting in subsequent 30 inconvenience.

The objects of this invention are to provide an evaporator free from the above objections, occupying small floor-space, and capable of a varied distribution of its corporate units.

With these objects in view the invention 35 consists, broadly, of an evaporation-chamber having a front opening at an angle to the perpendicular and covered by a sealed door internally cored to provide ports coinciding 40 with steam-inlets to a series of steam-coils attached to the said door. These coils extend into the water contained within the evaporation-chamber, a vertical outlet from the evaporation-chamber communicating with a separating-pile 45 consisting of a series of vertical tubes one within the other and alternately open top and bottom, whereby the vapor is caused to take a tortuous way to the outlet which is reached through a check or non-return valve 50 controlling the passage to the condenser or still, and with the necessary intercommuni-

cation—pipes and valves, &c.—between the several units in the battery.

In the drawings, Figure 1 is a front elevation of a battery of evaporators constructed 55 and arranged in accordance with this invention. Fig. 2 is a vertical cross-section of an evaporation unit of the battery. Fig. 3 is a diagrammatic plan view of a set of coils as arranged within the evaporating-chamber. Fig. 60 4 is a plan view in cross-section, taken on the levels Nos. 1 2 3 4, Fig. 2, of a combination of six units united with their respective evaporation-chambers cast as an integral whole.

In detail the construction consists of the 65 evaporating-chamber comprising the coil-space A, axially inclined from the perpendicular and within which the water and heating coils are contained, and the vertical dome A', from which the vapor escapes upward into 70 the separating-pile. The evaporating-chamber is preferably cast in one integral piece suitably cored to form the independent channels or ports A² and A³, coinciding with the similarly-formed ports in the cover or closure 75 A⁴, communicating through the gates B' in the terminal heads B² on the respective ends of the coils B. The said closure or cover A⁴ is securely sealed and bolted to the faced opening of the space A. 80

The separating-pile is securely sealed and bolted to the flanged upper opening of the dome A' and consists of a cylindrical chamber formed of the base C, into which the shell C' is screwed or brazed and which is 85 topped by the cap C², having the center opening C³ leading into the valve-chamber D against the valve-gate D', controlled by the stem D², extending upwardly through the stuffing-box D³ and supporting the pressure- 90 opposing weight D⁴. Entrance to the separating-pile from the evaporating-chamber is through the upwardly-extending tube C⁴, screwed into the center of the base C and topped by the downwardly-flanged cap C⁵, 95 having lateral gateways C⁶ leading to the space within the downwardly-extending shell C⁷, screwed into the flange C⁸ on the cap C⁵ and terminating near the base C.

Live steam is led from the boilers through 100 the main E, through the valves E' to the ports A², communicating with the coils B,

thence through the ports A³ to the exhaust-lead E², thence to the condenser. The globe of the valve E' permits an unobstructed passage of the steam along the main, the valve-5 seats controlling the inlet to the coils being below the path of the steam.

Sea-water being the principal liquid treated by this apparatus, this term will be used as comprehensively including any liquid purifiable by this process of treatment. Sea-water is pumped through the main F through the regulating-valves F' to the evaporation-chamber, the supply being regulated to compensate for the demands of evaporation, maintaining a mean water-level approximating that shown in Fig. 2—to wit, submerging about one-third of the surface of the heating-coils. This supply regulation is easily determined in practice, or it may be maintained 15 by any suitable means. The water-level is always indicated by the gage-glass G, attached to the most convenient unit in the battery and provided with the pipe connection G', open to the pressure within battery-outlet to 20 balance the pressure within the glass, for obvious reasons.

The evaporation-chambers of a battery may be combined, as shown in Fig. 4, in an integral casting with separating-webs to preserve 30 the independence of the various units. This is a desirable construction in special instances and is claimed as a part of the invention.

Operation: An evaporation plant consists of the combination of units as described above, 35 coöperating to produce the desired quantity of evaporation. The sea-water is permitted to flow into the apparatus to the desired level. The steam is turned into the main, passing into the coils at the top and downward through the 40 submerged portion, giving off its heat to the sea-water and raising the temperature of same to the point of evaporation. The vapor from the water rises among the convolutions of the coils, which are hottest at the top of the coil 45 and which tend to superheat the vapor, causing the precipitation of any salt or impurity that may be held in suspension in the vapor where the density of the latter is too great, which often results where violent bubbling is present. 50 From the evaporation-chamber the vapor rises into the separating-pile through the tube C¹, thence through the gateways C⁶, thence downward inside the shell C⁷, thence upward within the shell C⁷ to the condenser or any apparatus 55 for the further purification or distillation of the vapor, which apparatus does not enter within the scope of this present invention. The purpose of the separating-pile is to separate the heavier constituents from the vapor 60 and return them to the evaporating-chamber through the pipe C⁸. This is accomplished by condensation upon the walls of the tortuous passages within the pile. The "separated vapor" exerting its pressure lifts the weighted 65 valve-gate D' and escapes to its destination.

To guard against trapping the vapor by reason of an accumulation of water at the base of the evaporation-pile, the lower portion of the shell C⁷ is perforated at C⁹ to provide an emergency-passage for the vapor should the 70 said shell become sealed at its lower end by an accumulation of condensed vapors which for any reason have failed to pass off through pipe C⁸. Obviously as the water in the evaporation-chamber is evaporated it will become 75 denser and deposit scale on the coils unless drawn away from the influence of the heat. To this end the precipitation-legs H lead from the bottom of the evaporation-chambers downward a sufficient distance to accommodate the denser liquid. These precipitation-legs should be periodically washed out by opening them to the bilge or waste through the cocks H'.

Should the evaporator be forced beyond its 80 normal capacity, a slight saline or mineral deposit on the coils may result. The coils are easily rid of this deposit by draining off the water in the evaporation-chamber and permitting the increasing heat to expand the 90 coils, which can be readily contracted by rapidly filling the evaporation-chamber with cold water. The violent expansion and contraction results in cracking off the deposit.

A battery-evaporator such as described 95 may be arranged in circles, in rows, and variously disposed in angles or irregular places. The units may be connected in multiple, as shown, or in any other suitable manner. The particular advantage of the unit system, however, is the ability to cut one or more units out of operation without seriously crippling the apparatus as a whole.

Having thus described this invention, what is claimed, and desired to be secured by Letters 105 Patent, is—

1. An apparatus of the character described comprising an evaporating-chamber having its walls provided with independent channels, a closure for said chamber also provided with 110 independent channels coinciding with said former channels, inlet and outlet pipes communicating with the channels in said walls, and a coil of pipe having its terminals respectively connected with the channels in said closure.

2. An apparatus of the character described comprising an evaporating-chamber, a closure therefor, and heating-coils secured thereto, the wall of said closure being provided with 120 internal inlet and outlet channels with which the terminals of said coils communicate.

3. An apparatus of the character described comprising an evaporating-chamber, a closure therefor, and heating-coils secured thereto, the wall of said closure being provided with 125 internal inlet and outlet channels with which the terminals of said coils communicate, and means for separating the vapor arising from said chamber.

4. An apparatus of the character described, comprising an evaporating-chamber, a closure therefor, and heating-coils secured to said closure by terminal heads and provided with gates or ports, said closure being provided with inlet and outlet channels with which said gates or ports communicate.

In testimony whereof we have hereunto set our hands this 7th day of January, 1904.

HENRY C. TABRETT.
WALTER LEWIN.
